UNITED STATES PATENT OFFICE

SEUNG K. HAHN, OF PHILADELPHIA, PENNSYLVANIA

ENVELOPE

Application filed April 20, 1931. Serial No. 531,589.

This invention relates to an improved envelope and has more particular reference to accessory embodied in one end thereof to facilitate removal of the contents without danger of mutilating or tearing the contents.

More specifically stated, the invention is predicated upon a new type of envelope opener of the kind constituting an integral part of the envelope itself.

10 My principal aim is to generally improve upon articles of this type by providing a danger of mutilating or tearing the contents practical form of envelope opener characterized by simplicity and economy and capable 15 of fulfilling the desired result in a more satisfactory manner than is accomplished with the present type of openers with which I am now familiar.

In the drawings:

20 Figure 1 is a rear elevational view of an envelope constructed in accordance with the present invention.

Figure 2 is a view like Figure 1 showing the top or closing flap in its normal open position.

Figure 3 is a view like Figure 2 showing the improved opener in the process of construction.

Figure 4 is a view like Figure 1 showing the envelope opener torn off with the contents partly withdrawn and illustrated in dotted lines.

Figure 5 is a section on the line 5-5 of Figure 1.

Figure 6 is a horizontal section on the line 6-6 of Figure 2.

Figure 7 is a perspective view of one of the details.

Figure 8 is a perspective view of another one of the details.

In the drawings in Figures 5 and 6 for example the envelope as a whole is indicated by the numeral 9 and comprises the usual front wall 10 and as seen in Figure 2, the gummed closing flap is denoted by the numeral 11 and the panel sections 12 and 13 are fastened together along their meeting edges to form the back wall.

50 The lower end portion of the envelope is revised to incorporate the features of this

invention and I first call attention to the numeral 14 which designates the bottom closing flap. This has its inner surface coated with glue or other adhesive material as illustrated in Figure 3. It is approximately 55 rectangular in configuration and for sake of illustration of the principle of the invention may be said to comprise an upper section 15 and a lower section 16. The section 16 is opposed to a corresponding lower part 17 of 60 the front wall 10 and these features 16 and 17 are joined by the fold or bend 18 forming the bottom of the envelope. In accordance with the invention I provide an opener strip 19 which may be of fabric or other equivalent 65 material. This is fastened to the glue on the inner surface of the lower section 16 but is not attached to the panels 12 and 13. The numeral 20 designates a guide and reinforcing 70 strip of heavy paper or the like which is 70 glued to the outer surface of the section 15 and this strip has its ends 21 beveled on the approximate angle illustrated in the drawings. The purpose of these bevels is to form clearance spaces at opposite ends of the strip 75 20 to facilitate gripping of the end portion of the section 16 for downward and then lateral pulling. The lower edge of this strip 20 forms a straight edge which guides the tearing 80 or opening operation of the envelope. 80

In making the envelope it is observed that the portion 17 of the front wall 10 does not extend below the lower ends of the panels 12 and 13 (illustrated in Figure 5). Assuming that the flap 14 is swung down to the flat position illustrated in Figure 3 it is obvious that the fabric strip 19 is glued to the inner surface of the part 16. Then the part 15 is swung up and fastened to the adjacent lower end portions of the panels 12 and 13. Next the 90 strip 20 is glued across the outer surface of the part 15 so that it will serve as a reinforcing member as well as a straight edge for tearing purposes. By catching a hold of either end of the strip equipped section 16 95 and tearing crosswise on a line with the lower edge of the guide strip 20, it is obvious that the lower end portion of the envelope can be torn away without disrupting the contents of the envelope. Incidentally in Figure 6 I 100

have shown the features 16 and 19 partly torn and peeled back to indicate the manner in which the tearing is accomplished for conveniently exposed the contents of the envelope.

It is thought that the description taken in connection with the drawings will enable a clear understanding of the invention to be had. Therefore, a more lengthy description is thought unnecessary.

While the preferred embodiment of the invention has been shown and described, it is to be understood that minor changes coming within the field of invention claimed may be resorted to if desired.

Having thus described my invention, what I claim as new is:

In an envelope, a front wall provided at one end thereof with a flap having an adhesive, a back wall embodying overlapping panels flatly engaged by the edge portion of said flap, an envelope opening strip between said flap and the panel of said back wall and positioned adjacent the point of connection of said flap with said front wall, and a reinforcing strip secured to the outer surface of said flap and having a spaced lower edge in spaced parallel relation to one edge of said envelope opening strip, the end portion of said reinforcing and guide strip being extended angularly in from the sides of the envelope to facilitate tearing.

In testimony whereof I affix my signature.
SEUNG K. HAHN.
